Attorney

UNITED STATES PATENT OFFICE.

HERBERT O. TOMLINSON, OF WHEATON, ILLINOIS.

ELECTRIC-LIGHT FIXTURE.

1,320,809.

Specification of Letters Patent.

Patented Nov. 4, 1919.

Application filed April 21, 1919. Serial No. 291,616.

To all whom it may concern:

Be it known that I, HERBERT O. TOMLINSON, a citizen of the United States, residing in the city of Wheaton, in the county of DuPage and State of Illinois, have invented new and useful Improvements in Electric-Light Fixtures, of which the following is a specification.

This invention relates generally to electric-light fixtures and has for its object the provision of a fixture including a support or holder for an electric-light diffusing bowl or globe, which is simple in construction and ornamental in use.

Another object is to provide a fixture of this character with a holder which shall be responsive and accommodating to the expansion of the globe due to the heat of the electric lamp. This expansion is afforded in the peculiar construction which employs the use of three independent sections to form the single holder which has arms spirally twisted together but with an untwisted portion of substantial length between the inner end of each spiral twist and the annulus.

With these and other objects in view, my invention consists in the novel construction, combination, and relative position of the parts and members hereinafter described and shown in the accompanying drawings, and particularly pointed out in the appended claims.

A structure embodying my invention is illustrated in the accompanying drawings, in which Figure 1, is an elevation of same, and Fig. 2, a plan view of the holder.

Referring to the illustrations, 10 indicates an electric lamp carried in the socket which carries a suitable reflector-support 12. The glass reflector 13 is held in the support 12 by screws 14.

The translucent glass diffusing bowl or globe 15 is preferably formed with the extending flange 15^A for support in my improved holder generally designated by numeral 16.

The holder 16 is preferably made of three independent pieces of round wire 16^A formed into a ring 16^B. The ends of each wire 16^A extend upwardly or perpendicularly to the plane of the ring 16^B and are locked or secured together with the adjacent ones by spiral twists 16^C which not only tie

the three sections together but also form stiffened upwardly extending arms 16^D. 55 The extreme ends 16^E of the two wires are bent to form inwardly disposed hooks 16^F which engage the edge of the reflector 13 and thereby suspend the bowl 15 from said edge. 60

The bowl 15 can readily be removed by first springing the arms 16^D outwardly to disengage the hooks 16^F from the edge of the reflector 13. The bowl 15 can then be lifted out of the annulus 16^B. Attention is directed to the resiliency of the structure disclosed which is attained by beginning the twisted section at a point G a distance substantially about the plane of the annulus so that three sections are free to spread apart 70 in response to any possible expansion of the bowl rim or flange 15^A due to the heat generated by the electric lamp 10.

With the construction shown and described, the sectional or non-continuous ring 75 16^B composed of sections 16^A does not need to be flanged to underlie or support the flange 15^A, and the arms 16^D do not need to be attached in any way to the ring-like bowl holder, as these arms are integral with said 80 sections.

It is thought that the foregoing description and illustrations clearly disclose the construction and operation of the invention, hence a more extended explanation is 85 omitted.

I claim:

1. The combination of an electric lamp, reflector, a light diffusing bowl below said reflector, an expandable annulus encircling 90 the top portion of said bowl, formed of separate wires having their end portions twisted together to form hooks to engage the edge of the reflector, all of said hooks being untwisted a substantial distance from the 95 annulus to permit expansion of the annulus, substantially as shown and described.

2. In a lighting fixture, the combination of a lamp socket, a holder with a substantially flat downwardly flaring reflector supported on said socket, a bowl supported below said reflector, and means for supporting said bowl comprising a plurality of wire members forming a substantially fixed but elastically expandable annulus, the adjacent 100 ends of said members forming arms extend-

ing upwardly from the plane of said annulus and having inwardly disposed hook formations at their extremities to engage the edge of said reflector, said arms being spirally twisted together at their intermediate portions, and having a substantial untwisted portion between the inner end of

each spiral twist and the annulus to afford elastic expansion of the annulus.

In witness whereof, I have hereunto subscribed my name this 18th day of April, 1919.

HERBERT O. TOMLINSON.
